UNITED STATES PATENT OFFICE.

JOHN JAMES PATTERSON, OF COEUR D'ALENE, IDAHO.

TOOL.

1,142,617.

Specification of Letters Patent.

Patented June 8, 1915.

Application filed April 4, 1914. Serial No. 829,507.

To all whom it may concern:

Be it known that I, JOHN J. PATTERSON, a citizen of the United States, and a resident of Coeur d'Alene, in the county of Kootenai 5 and State of Idaho, have invented a new and Improved Tool, of which the following is a full, clear, and exact description.

An object of my invention is to provide a simple tool, having means to secure it to a bench or like support, and possessing marked practicability as a clamp for cabinet makers and wood working, or as a vise convertible for use either as a pipe vise, or for filing and other general vise work, and 10 embodying wrench elements detachable from the base and securing devices, and adapted to constitute an efficient tool convertible into either a pipe wrench or a monkey wrench.

Other objects of the invention are to embody in a device of the indicated character, 15 handled clamp jaws so constructed and arranged as to exert the necessary force to break a corroded pipe joint without danger of crushing the pipe; to provide wrench elements by means of which the pipe may be turned in either direction without reversing the tool or removing it from the pipe; to provide for a quick release of a gripped object; and to provide wrench elements adapt- 20 ed for use as a monkey wrench, which may be rocked backward on a nut from face to face of the nut without removing the tool from the nut.

The invention will be particularly explained in the specific description following.

Reference is to be had to the accompanying drawings forming a part of this specification, in which similar characters of reference indicate corresponding parts in all 25 the views.

Figure 1 is a side elevation of a tool embodying my invention and arranged for use as a clamp or vise; Fig. 2 is a plan view with parts arranged as in Fig. 1; Fig. 3 is a detail cross section on line 3-3 Fig. 1; Fig. 4 is a perspective view of an auxiliary jaw for the main fixed jaw; Fig. 5 is a detail longitudinal sectional view of portions of the forward end of the tool, with the 30 parts adjusted as in Figs. 1 and 2; Fig. 6 is a detail cross section on the line 6-6 of Fig. 5; Fig. 7 is a side elevation showing the tool arranged as a pipe vise for holding a pipe while operating thereon, as with a die. 35 Fig. 8 is a side elevation of the wrench elements of the tool arranged for use as a pipe

wrench; Fig. 9 is a side elevation of the wrench elements of the tool arranged for use as a monkey wrench; Fig. 10 is a detail side view with parts broken away, showing 40 the jaws of the tool equipped to constitute a pipe cutter; and Fig. 11 is a detail plan view of the fixed jaw shown in Fig. 10.

Referring particularly to Figs. 1 to 6, my improved tool is illustrated as comprising 45 a jaw 10, which will constitute a fixed jaw, and a rigid handle 11 extends rearwardly from the base of said jaw. In order to detachably secure the handle 11 of the fixed jaw to a bench 13 or like support, a base 50 12 is provided, here shown as consisting of an oblong, thin plate which may be secured by screws 12^a or the like to the top of the bench 13. To seat the jaw 10 firmly on the base 12, the latter has its forward end 55 14 upturned and formed with a depression 15 (Fig. 3) constituting a seat for receiving the bottom of the jaw 10. In order to clamp the handle 11 securely I provide clamping means in connection with the base adjacent 60 12 to the jaw 10, said clamp means being here shown as consisting of a hook bolt 16, which extends downward through the base 12, and in practice, also through the bench top 13. A wing nut 17 or the like on the lower 65 threaded end 16^a of the shank of the hook bolt 16, serves to tighten the said bolt, whereby the handle will be effectively held on the base with the fixed jaw 10 firmly seated in the seat 15.

In connection with the handled fixed jaw as described, I provide a relatively movable jaw 18, having a fixed handle 19 slideable and rockable relatively to the first handled jaw, as hereinafter described, to adjust the 70 jaws. Associated with the base 12, I provide means for holding the handle of the movable jaw in adjusted relation to the fixed handle and to the base. Said means may consist of an upstanding fork 20 having its 75 bottom 20^a in rigid relation to the base 12, and presenting spaced upstanding side members receiving both the handles 11 and 19. The handle 11 is adapted to seat on the bottom 20^a and the movable handle 19 may assume various positions in the fork 20. The sides of the fork are formed with registering vertical slots 21, and a tapered key 22 is movable in said slots above the handle 19, so as to hold the latter in adjusted position.

Various means may be employed for effecting the sliding and rocking movement

of the handled movable jaw. As here shown, a loose member 23 in the form of a boxing is fitted on the movable handle 19, adjacent to the fixed jaw 10 and is pivoted 5 to the latter by a pin 24 or the like. The rear end of the loose member 23 has a fork 25, which is received in an annular groove 26^a on a sleeve 26, said sleeve 26 being internally threaded and turning on a threaded 10 portion 27 of the handle 19. The arrangement is such that the handle 19 may be rocked on the pivot 24, and it may be moved longitudinally by turning the sleeve 26, so that the longitudinal movement may effect 15 an approximate adjustment of the jaws and a rocking movement to complete the gripping action of the jaw, the key 22 and fork 20 serving to hold the said handle in adjusted position.

20 The handled jaws and the means for securing the same to a bench as described, it will be obvious, give the tool the general character of a vise or a clamp. To adapt the jaws of the vise for use as a pipe vise, the 25 opposed faces of the jaws are formed with gripping teeth, there being reversely disposed series of gripping teeth 28, 29, on the fixed jaw, at angles to each other and defining a V-shaped recess. Similarly there 30 are formed on the movable jaw reversely disposed series of gripping teeth 30, 31. The teeth 28, 30, on the corresponding portions of the respective jaws are alike, which is true also of the teeth 29, 31, on said jaws; 35 while the obliquely opposite teeth 28, 31 and 29, 30 will be reversed. The form and disposition of the teeth give an effective gripping action for the pipe when the tool is used as a pipe vise and, as will hereinafter 40 appear, the teeth are effective when the handled jaws are detached from the base to constitute wrench elements.

The fixed jaw 10 is formed with spaced 45 sides defining an intermediate opening 10^a, and the movable jaw 18 is sufficiently narrow that it may partially enter between the spaced sides of the fixed jaw, so that the series of gripping teeth may engage a pipe or 50 nipple of very small diameter.

55 In order to provide plain jaw elements auxiliary jaws are provided attachable to the main jaws as follows: On the fixed jaw 10 there is an auxiliary jaw comprising a face plate 32 and a lug 33 at the back of the plate, said lug being receivable in the opening 10^a between the sides of the fixed jaw, while the face plate 32 bridges the V-shaped recess and seats against the said fixed jaw above and below said recess. The auxiliary jaw 60 is secured by a cotter pin 34 or the like, which passes through registering holes 35 in the sides of the fixed jaw 10, and a hole 36 in the lug 33. A mating auxiliary jaw is 65 removably secured to the movable jaw 18, and consists of a face plate 37 bridging the

V-shaped recess in the movable jaw and rearwardly extending side flanges 38 that overlap the sides of the movable jaw and receive a fastening pin 39 which extends through holes 40 in the flanges 38, and to a 70 registering hole 41 (Fig. 5) in the movable jaw 18.

When the vise is to be employed for holding an article to be filed, or for general vise work, or when the jaws are to be used for 75 clamping an article, as in cabinet work or the like, the plain auxiliary jaws are secured in position. There is conventionally indicated at 42 in Figs. 2 and 5, an article clamped between the auxiliary jaws. This 80 may represent an article to be filed; as will be evident, any other piece of metal or woodwork requiring to be clamped may be effectively held between the plain faces of the auxiliary jaws. 85

The described means for securing the handles to a bench, and the form and arrangement of the handles and jaws, provide for the removal of the handled jaws and their effective use as a wrench. Thus in 90 Fig. 9, the wrench elements, including the auxiliary jaws, are shown as adapted for use as a monkey wrench, for turning a nut 43.

In Fig. 8, with the auxiliary jaws removed, an effective pipe wrench is provided, 95 there being indicated a nipple 46 on a structure 47. In either form of the wrench the latter can be turned in either direction without removing it from the pipe and reversing it from its position, as is necessary for 100 instance, with the Stilson and the monkey wrench. The handles may be relatively rocked, so that the wrench may be turned backward on the pipe or nut, and again 105 quickly brought into clamping position.

In Fig. 7, the vise is shown with the auxiliary jaws removed so that the tool constitutes a pipe vise, in which the serrations 110 28 to 30 will effectively bind a pipe 44 for using a die 45 or other tool on the pipe. With the serrated gripping surfaces 28 to 31 disposed as described, the danger of 115 crushing a pipe is minimized because the pressure is exerted on two lines at right angles to each other, the pressure on the respective lines thus resisting each other.

Referring particularly to Figs. 10 and 11, it will be seen that the main jaws 10, 11, are equipped with special removable features to adapt the wrench elements for use 120 as a pipe cutter. Thus a face plate 48 bridges the V-shaped recess of the fixed jaw and has rearwardly projecting lugs 49 entered between the side members of said jaw and secured by a cotter pin 50 or the like. A rotary cutter 51 and a pin 52 is mounted 125 between the lugs 49 and projects through the face plate 48. On the opposite movable jaw 18 an auxiliary jaw is applied, presenting a V-shaped face plate 53, and rear- 130

wardly projecting side lugs 54 at the bottom, that overlap the sides of the movable jaw 18 and are secured by a cotter pin 56 or the like, extend through holes 55 in the 5 said flanges and through a registering hole in the said movable jaw.

By the described construction it will be seen that the wrench elements now will constitute an effective pipe cutter.

Having thus described my invention, I claim as new and desire to secure by Letters Patent:

1. In a tool of the character described, a base having means whereby to secure it to a bench or the like, and having an upturned end formed with a depression constituting a seat, upstanding spaced elements on the base distant from the seat, a clamp jaw fitting the seat of the base and having a rigid 15 handle extending from its lower end between the upstanding members, a hook bolt engaging the said handles adjacent to the said seat and extending downwardly through the base, a clamp nut on said shank, 20 a second jaw having a rigid handle pivotally connected with the fixed jaw to rock toward and from the first handle, and movable longitudinally relatively to the first 25 jaw and its handle, the said handle of the second jaw extending between the upstanding members, and means associated with the said upstanding members to hold the respective handles of the jaws in adjusted relation.

2. In a tool of the character described, a 35 fixed jaw having a rigid handle, a movable jaw having a handle pivotally mounted to be rocked toward and from the first handle, clamp means to secure the first handle to a bench or like support, upstanding members 40 separate from said clamp means and independently securable to a bench or other support for receiving said handle, and means associated with the upstanding members to hold the handles in adjusted relation to each other.

3. In a tool of the character described, a

fixed jaw having a rigid handle, clamp means to secure the first handle to a bench or like support, a movable jaw having a handle and mounted to be rocked toward and from the first handle, and to have longitudinal movement relatively to said first handle, a U-shaped member having spaced sides adapted to receive both the fixed handle and the handle of the movable jaw, the said sides 50 being slotted, and a tapered key fitting the slots and adapted to hold the handles in adjusted relation.

4. In a tool of the character described, a pair of handled jaws connected for relative 60 rocking and sliding movement, means for securing one of the handles to a bench, or like support, and means adapted to be secured to the support and to hold the other of said handles in adjusted relation to the 65 first handle and to the support.

5. In a tool of the character described, a base, a pair of handled jaws rockable and slideable relatively to each other, means to secure one handled jaw to the base, and 70 means on the base to engage both handles and hold the same in adjusted relation to each other.

6. In a tool of the character described, a handled jaw, means for detachably securing 75 the same to a fixed support, a second handled jaw rockable and slideable relatively to the first handled jaw, and means adapted to embrace both handles for holding the handle of the second jaw in adjusted relation to the first handle when the latter is in a fixed position, said second means being securable to a fixed support, independently 80 of the first means.

In testimony whereof I have signed my 85 name to this specification in the presence of two subscribing witnesses.

JOHN JAMES PATTERSON.
